[57] ABSTRACT

Fixed blading for an axial compressor constituted by a succession of blades fixed on at least one annular wall and a method of operating the same. Fluid passing through a passage between adjacent blades is drawn into a suction opening and the pressure at the suction opening is maintained substantially equal to the flow static pressure in the passage.

FIXED BLADING OF AXIAL COMPRESSORS

The invention relates to fixed blading for axial compressors, such fixed blading being constituted by arrays of blades each comprising a succession of blades borne by an annular lateral wall, or interposed between two annular lateral walls, this or these annular lateral walls extending transversely between the blades of the array of blades.

The present invention also relates to a method of operating such an axial compressor.

Among the more particularly advantageous applications of the invention, there may be mentioned the application to axial compressors for aircraft turboreactors.

It has already been suggested to form in the one or more annular lateral walls suction openings arranged between two successive blades and connected to aspirating means; these suction openings enabling the reduction of disturbances due to the boundary layer which is developed on this or these annular lateral walls.

In fact, these disturbances affect the two dimensional character of the flow and cause an increase in the losses undergone by the flow through the array of blades.

It is an object of the invention to provide a particularly advantageous shape and arrangement of these suction openings.

According to the invention each suction opening has elongated shape and extends over the whole width of the passage defined by two successive blades, between an under surface region or intrados (side subjected to increased pressure) of a blade situated towards the leading edge and a back surface region or extrados (side subjected to reduced pressure) of the following blade situated at one half or preferably one third of its length, from its leading edge.

Due to the shape and arrangement of such aspirating openings, which shape and arrangement have been perfected by applicant after numerous aerodynamic tests, it is possible to give the aspirated flow a suitable value to cause localised suction of the boundary layer enabling the elimination or considerable reduction of the disturbances due to this boundary layer.

According to a preferred feature of the invention, the suction means are arranged so that the pressure at the level of the suction openings is of the same order of magnitude — that is to say substantially equal — to the static pressure of the local flow in the passage concerned.

The invention further relates to a method for operating such an axial compressor wherein fluid aspired through the passages between adjacent blades is maintained at a pressure substantially equal to the flow static pressure in the passage.

The invention will in any case be well understood with the aid of the additional description which follows as well as of the accompanying drawings, which complement and drawings relate to various embodiments of the invention and are not of course to be regarded as limiting in character.

In the drawings:

FIG. 1 shows a partial diagrammatic perspective view of fixed blading for an axial compressor, constructed in conventional manner, and in which there are shown by various arrows the flow disturbed by the boundary layer which is developed on the annular lateral wall.

FIG. 2 shows, under the same conditions, this fixed blading constructed according to the invention and in which the flow represented by the various arrows is perfectly bidimensional.

FIG. 3 is a partially developed view of fixed blading constructed according to the invention.

Lastly, FIG. 4 is a diagrammatic section along the line IV—IV of FIG. 3.

The fixed blading shown in FIGS. 1 and 2 is constituted by an array of blades comprising a succession of blades 1 borne by an annular lateral wall 2 on which said blades 1 are fixed by one of their two ends. For clarity of the drawing there is shown a single annular lateral wall, but the blades can also be interposed between two concentric annular lateral walls.

In FIG. 1, there is involved conventional fixed blading and the boundary layer which is developed on the annular lateral wall 2 causes disturbances of flow in the passages defined by two successive blades; these disturbances are constituted by detachments and vortexes which create an artificial convergence of the flow into the abovesaid passages.

There is shown in this FIG. 1, by different arrows, the disturbed flow in the vicinity of the annular lateral wall 2. This disturbed flow involves the blade 1 over a considerable length since the orientation of the line L enveloping the zone affected by the detachments and the vortexes is about 45° with respect to the direction in which the blade extends.

This being the case, there is formed in the annular lateral wall 2 — or in the two concentric annular lateral walls — a suction opening 3 connected to suction means.

According to the invention, and as illustrated in FIG. 2, this suction opening 3 has elongated shape and extends over the whole width of the passage defined by two successive blades, between an under surface region of one blade situated towards its leading edge and a back surface region of the following blade situated at half or preferably one third of its length, from its leading edge.

It will be noted that the shape of the suction opening 3 is elongated and oriented parallel to the isobars of the local pressure field and that the arrangement of the suction opening 3 is such that said suction opening 3 occurs in the passage concerned, in a region where the pressure gradients reach maximal values.

As regards the suction means — which will be more explicitly considered below — it can be arranged so that the pressure at the level of the suction openings is of the same order of magnitude as the static pressure of the local flow in the passage concerned.

As shown in FIG. 2, by different arrows, the flow in the fixed blading, constructed according to the invention, has a bidimensional character over all of the blades, given that the boundary layer on the annular lateral wall 2 has been trapped and that the detachments and vortexes have been eliminated.

In FIG. 3 there is shown a partial view of a planar projection of the fixed blading shown in perspective in FIG. 2.

In the neighbourhood of the undersurface of the blade, the suction opening 3 has a rounded shape, whilst in the neighbourhood of the back surface of the following blade the suction opening 3 has a shape matching the airfoil of the blade. From the constructional point of view, the suction opening 3 can be ex-

tended below the latter blade beyond its back surface, the corresponding edge of this suction opening 3 then being bounded by the fraction of the back surface of the blade situated above the said suction opening.

In FIG. 4 there is shown in axial section the fixed blading of FIG. 3, the rotor of the compressor being denoted by the reference numeral A and the two movable blade assemblies of the compressor, surrounding the fixed blade assembly according to the invention, being denoted by the reference numerals B₁ and B₂ respectively.

As shown in this FIG. 4, the suction opening 3 can include an upstream edge 3a perpendicular to the annular lateral wall 2 in which it is formed, and a downstream edge 3b oblique and forming an acute angle with the abovesaid wall. This arrangement facilitates the suction of the boundary layer.

As regards the suction means, they can be of different natures according to the conditions of use of the compressor.

In particular these suction means can be servocoupled, as regards the value of the flow aspirated, to various characteristics of the compressor. In particular they can be servocoupled to the rotary speed so that the ratio of the flow aspirated to the flow of the stream passing through the compressor remains constant.

These suction means can, as shown in FIG. 4, comprise a buffer space 13 from which the aspirated fluid is evacuated by means of a restricting device comprising, for example, a fixed constriction 14 and/or a regulating valve 15.

This regulating valve 15 can then be governed by a regulator 16 acting as a function, on one hand, of the static pressure of the flow upstream of the fixed blade assembly (which static pressure can be transmitted through an aperture 17 formed in a suitable place of the compressor) and, on the other hand, of the static suction pressure (static pressure transmitted by an aperture 18 formed in the buffer space 13).

In certain cases, there may be provided a porous or perforated wall 19 (shown in mixed line in FIG. 4), arranged in the suction opening 3 and limiting the flow-rate of aspiration.

The flow of fluid aspirated by the group of suction openings 3 can be ejected to the atmosphere, or advantageously be used for other purposes.

This latter possibility is particularly advantageous when it relates to the application of the invention to axial compressors for aircraft turbo-reactors; the fluid aspirated from the fixed blade assembly through the suction openings can be used as a driving fluid, or even as a cooling fluid for other members (turbine, air-conditioning apparatus, etc.). It will be noted that this arrangement then renders unnecessary the take-off members generally provided in such compressors.

The fluid sucked into the fixed blade assembly can also be reinjected further upstream into the compressor by means of a suitable device arranged to obtain a blast or parietal effect with a view to reabsorbing possible detachments and further improving the overall yield of the compressor.

We claim:

1. Fixed blading for an axial compressor constituted by a succession of blades fixed on at least one annular wall, each passage between two adjacent blades being provided with a suction opening, suction means associated with said suction opening for aspiring fluid

through the suction opening, said suction means including means for maintaining the pressure in the suction opening substantially equal to the flow static pressure in the said passage.

2. Fixed blading according to claim 1, wherein each suction opening comprises an upstream edge perpendicular to the annular lateral wall and an oblique downstream edge forming an acute angle with the abovesaid annular lateral wall.

10 3. Fixed blading according to claim 1, wherein each suction opening comprises a porous or perforated wall arranged to limit the aspirated flow-rate.

4. An aircraft turbo-reactor axial compressor, comprising fixed blading according to claim 1.

15 5. Fixed blading according to claim 1, said suction means including means for maintaining constant the ratio of the flow rate of the fluid aspirated through the said suction opening to the flow rate of the fluid flowing through the said passage.

20 6. Fixed blading according to claim 1, said suction means including a regulator device operatively connected to the suction opening to regulate the suction pressure as a function of a particular pressure of the flow passing through the passage.

25 7. Fixed blading according to claim 1, including means for exhausting to the atmosphere the fluid aspirated through the suction opening.

30 8. Fixed blading according to claim 1, including means for delivering the fluid aspirated through the suction opening to at least one other stage of the compressor situated upstream from said fixed blading for producing thereat a control effect on the boundary layer by a blast effect.

35 9. Fixed blading according to claim 1, said suction opening having an elongated shape extending across the whole width of said passage between an undersurface region of one blade situated towards its leading edge and a back surface region of the following blade situated in the first half of its length from its leading edge.

40 10. Fixed blading according to claim 9, wherein the suction opening extends between an undersurface region of a blade situated towards its leading edge and a back surface region of the following blade situated about two thirds of its length from its leading edge.

45 11. Fixed blading according to claim 1, said suction means including a buffer space adjacent the suction opening for receiving the fluid passing therethrough.

50 12. Fixed blading according to claim 11, including an exhaust means for controllably delivering fluid out of said buffer space, and means responsive to the flow static pressure in the passage and to the pressure in the buffer space for controlling the flow rate through the exhaust means.

55 13. A method of operating an axial compressor of the type constituted by a succession of fixed blades fixed on at least one annular wall of the compressor, comprising the steps of:

aspirating fluid from each passage between two adjacent blades through a suction opening, and maintaining the pressure in the suction opening substantially equal to the flow static pressure in the passage.

60 65 14. A method according to claim 13, including delivering the fluid aspirated through the suction opening into a buffer cavity, controllably delivering the fluid out of the buffer cavity, sensing the static flow pressure in the

passage, sensing the pressure in the buffer cavity, and controlling said delivery in response to both of said sensed pressures.

15. The method of claim 13, including maintaining constant the ratio of the flow rate through the suction opening to the flow rate of fluid through the passage.

16. The method of claim 13, including the step of delivering the aspirated fluid to the atmosphere.

17. The method of claim 13, including delivering the aspirated fluid to at least one stage of the compressor upstream of the fixed blading to produce thereat a control effect on the boundary layer by a blast effect.
